FIG. 2.

Inventor:

Walter T. Forbes
By W. T. C. Chandler, Atty.

UNITED STATES PATENT OFFICE.

WALTER T. FORBES, OF ATLANTA, GEORGIA.

REFRIGERATOR.

SPECIFICATION forming part of Letters Patent No. 397,791, dated February 12, 1889.

Application filed May 16, 1888. Serial No. 274,114. (No model.)

To all whom it may concern.

Be it known that I, WALTER T. FORBES, a citizen of the United States of America, and a resident of Atlanta, in the county of Fulton 5 and State of Georgia, have invented a new and useful Refrigerator; and I do hereby declare the following to be a full, clear, and exact description of the invention, such as will enable others skilled in the art to which it appertains 10 to make and use the same, reference being had to the accompanying drawings, and to letters and figures of reference marked thereon, which form a part of this specification.

This invention has for its object the more 15 economical use of ice in the cooling of refrigerators, and also to prevent the accumulation of moisture therein; and it consists of pipes and flues to conduct the air that is caused to circulate by its constantly-changing tempera- 20 ture without coming in contact with the ice, the details of all of which will be hereinafter fully set forth, and the parts thought to be new pointed out in the claims.

In the accompanying drawings, Figure 1 is 25 an elevation, partly in section, on the line 1, Fig. 2, showing the interior of the refrigerating-chamber and the interior of the ice-chamber, also showing the pipes in the ice-chamber, the flues leading thereto and the pipe 30 leading therefrom, the waste-water coil of pipes, and the valves for draining the waste-water pipes. Fig. 2 is a top view with the cover removed, showing the interior of the ice-chamber of the ice-box and the flues leading 35 thereto, and having connection by perforations with the interior of the refrigerator. Fig. 3 is a perspective view of the system of pipes that is in the ice-box with its inlet and outlet.

40 In the several views, like reference-marks indicating corresponding parts, B is the interior of the refrigerating-chamber, and C is the interior of the ice-chamber. These chambers may be constructed in any approved 45 manner that will furnish walls that will afford the proper resistance to the transmission of heat. The construction of these chambers so long as they fill these requirements being immaterial, I have shown them of the 50 ordinary construction in refrigerators—that is, having outer and inner walls, the interven-

ing space being filled with charcoal, mineral wool, or other non-conducting material. It is also immaterial that the ice-chamber be placed at the side of the refrigerating-chamber, as it may be placed within it, the pipes and flues leading the air to and from it in the same manner as that hereinafter described for the form of construction shown, which, however, in all of its details is con- 55 sidered preferable. The ice-chamber is provided with a removable cover at the top, which need never be opened excepting for the purpose of putting in ice, by reason of which and by reason of the system of drain- 60 age and the system of carrying and cooling the air for refrigerating-chamber the ice need never come in contact with the outer air after being placed in the ice-chamber. 65

The chambers B and C are connected together with pipes and flues to provide for the transfer of heat from the refrigerating-chamber to the ice-chamber by convection, the air expanding by the absorption of heat passing upwardly and through the holes d, 70 and through the flues D and D' and through the pipes that surround the ice in the ice-chamber in the form of a cage, and consisting of the pipes X, Y, and Z, the inlets F and G, connecting with flues D and D', and the pipes 75 z, connecting by a five-way joint with the pipe E, thus placing the greater part of the pipe-area in the position that the ice will until exhausted come in direct contact with it. The air in these pipes on being cooled and con- 80 tracted will pass by gravity back into the refrigerating-chamber through the pipe E. The pipes in the ice-chamber should be arranged substantially as shown in the drawings, but best shown in Fig. 3—that is, they should 85 have inlet-openings F and G at the top to connect with the flues D and D', as shown in Fig. 2, and outlet-pipe E to conduct the air that has been rendered heavier by the removal of a portion of its heat to the chamber 90 B, where it immediately goes to the bottom and rises as it becomes expanded by the absorption of heat to again make the circuit, as 95 above described.

It is obvious that, the ice being isolated in 100 a chamber such as that shown and resting against the pipes forming said chamber, heat

will be absorbed from the air that they contain at any temperature above 32° Fahrenheit, until a sufficient quantity of heat shall have been absorbed by the ice to furnish the necessary sensible and latent heat to liquefy it, and that the air condensed by cooling will descend by gravity into the refrigerating-chamber and force upwardly the air that shall have become lighter by the absorption of heat from the contents of that chamber and continually make the circuit of that chamber and pipes as above described, and that the air will make the circuit with a rapidity in proportion to the quantity of heat given off by the contents of the refrigerating-chamber and the area of the contact of the ice with the pipes. For the latter reason I place the greater portion of the pipe-area in the bottom of the ice-chamber. The water resulting from the melting ice is carried by the pipe L, connecting with the interior of the ice-chamber, to the upwardly-inclined pipes M, through which it passes successively, each of these pipes excepting the last being bent down from its point of highest inclination and connected to the lowest end of the next inclined pipe M below it, the last one of the series being instead connected to the drain-pipe N, as are the projecting lower ends of all of the pipes M. The pipes M are provided at a point near their intersection with the drain-pipes with stop-cocks n. To prevent these pipes from freezing in extremely cold weather, all of the water therein may be drawn off through these stop-cocks and the pipes N; but at all other times these stop-cocks should be closed to force the water to make the circuit of the pipes M for the purpose of causing it to absorb any excess of heat in the refrigerating-chamber over that in the water resulting from the melting ice.

It will be observed that in this device the air does not come in contact with the melting ice, and consequently does not absorb from it any moisture, but will remain in a condition that will be the least likely to convey from one article in the refrigerating-chamber the peculiar odor of that article to another. 45

Having thus described my invention, what I claim as new, and desire to secure by Letters Patent of the United States, is—

1. The combination, in a refrigerator, of a provision-chamber provided with flues in its ceiling communicating through a series of perforations with the interior of the chamber, 55 of an ice-receptacle attached to the upper portion of said chamber, but completely separated therefrom, a series of connected air-pipes arranged in said receptacle and communicating at the upper part thereof with said flues, a curved pipe connected to the lower part of said series and opening into the provision-chamber near the bottom thereof, and a tortuous drip-pipe leading from the ice-receptacle through the provision-chamber. 60 65

2. In a refrigerator to drain the ice-chamber and utilize the refrigerating properties of the water so drained from said ice-chamber, the inclined pipes M, connected to the ice-chamber, each pipe being bent downwardly 70 at its higher end and connected to the lower end of the pipe next below, and the stop-cocks n on the outside of the chamber and connected with the lower ends of the pipes M, substantially as shown and described, and for 75 the purpose specified.

In testimony whereof I hereunto affix my signature in presence of two witnesses.

WALTER T. FORBES.
